AIR CONDITIONING SYSTEM

Samuel S. Lawler, Minneapolis, Minn., assignor to
 Minneapolis-Honeywell Regulator Company,
 Minneapolis, Minn., a corporation of Delaware

Application August 11, 1938, Serial No. 224,413

17 Claims. (Cl. 236—11)

The present invention is related to an air conditioning system and more particularly to one in which there is a shut-down period during certain portions of the day.

It is the usual practice in air conditioning systems for a residence, particularly in the case of heating systems, to provide for a night shutdown period. In the case of a heating system, considerable saving in fuel may be effected by reducing the temperature maintained at night. Furthermore, it is quite common to open the windows of those rooms used for sleeping purposes and it obviously is undesirable for any appreciable amount of heat to be conducted to the rooms while the windows are thus open. In order to conserve heat, it is quite customary in the case of a warm air heating system, for the occupant of the room opening the window to also close the register. Sometimes this is not done, however, with the result that considerable heat is wasted through the open window. The opening of the windows further introduces a serious problem during the "pick-up" period in the morning. While the temperature may have been reduced in the downstairs portion or the portion of the house normally occupied during the day, the temperature therein will normally still be considerable higher than the temperature of those rooms used for sleeping in which the windows have been open all night. Accordingly, when it is attempted to restore the temperature to normal in both the normally occupied and the sleeping zones, either an excessively long time is required for such restoration of the temperature or the heat must be delivered to both zones at such an excessive rate that the temperature in the normally occupied zone becomes excessively high.

An object of the present invention is to provide an air conditioning system for a plurality of zones wherein the proportionate amount of air delivered to one zone is decreased below normal for a predetermined period and at the end of the period is temporarily increased above normal.

A further object of the invention is to provide such a system in which the temporary increase in the proportion of air to one zone is maintained until the condition in said zone attains a predetermined value.

A further object of the invention is to provide such a system in which the temporary increase in the proportion of air to one zone is maintained for a second predetermined period of time.

A still further object of the invention is to

provide a warm air heating system for a residence having a sleeping zone and a living zone with means for reducing the temperature in both zones and reducing the proportionate amount of air delivered to the sleeping zone at night and for increasing the proportionate amount of air delivered to the sleeping zone when it is desired to restore the zone temperature to normal.

Other objects of the invention will be apparent from a consideration of the accompanying specification, claims, and drawings, of which:

Figure 1 is a schematic view of a warm air heating system employing one form of the present invention, and in which:

15 Figure 2 is a schematic showing of the control portion of a modified form of the invention.

Referring to Figure 1, the warm air furnace is generally indicated by the reference numeral 10. This furnace is shown for purposes of illustration as being of the gas burning type containing a burner (not shown) supplied with gas through a pipe 11 connected to a valve 12 which, in turn, is connected to a gas supply pipe 13 leading from any suitable commercial source of gas (not shown). The valve 12 is shown as being of the motorized type which upon energization thereof is moved to open position and upon deenergization thereof is moved to closed position by some biasing means.

30 Extending from the furnace 10 is a warm air delivery duct 15. This duct is divided into two branch ducts 16 and 17, the branch duct 16 leading to a register 18 which is located in an upstairs or sleeping zone 19. The duct 17 leads to 35 a register 21 which is located in the downstairs zone 22 or one normally occupied during the day. While only one register has been shown for each zone, it is to be understood that each zone may consist of a number of rooms and branch ducts

40 may lead from the pipes 16 and 17 to these various zones with an individual damper at each register for opening and closing the zone in the normal manner. The proportionate amount of air delivered to pipes 16 and 17 is controlled by 45 a splitter damper 25. This damper is pivoted at 26 and has an arm 27 secured thereto for actuating the same. The outer end of arm 27 has secured thereto a spring 28 which, in turn, is secured to a fixed support 29. The spring 28

50 serves to bias the arm upwardly. The function of the splitter damper is to proportion the air between the two ducts 16 and 17 and it is to be understood that any further branch ducts leading to individual rooms are connected to pipes 16 and 17 beyond the splitter damper 25.

Cold air registers 30 and 31 are provided in zones 19 and 22, respectively. The cold air register 30 communicates with a return air duct 33 and register 31 with a duct 34. The two ducts 33 and 34 lead to a common return air duct 35 which returns to the furnace in the conventional manner (not shown). A damper 40 is provided in the duct 33. This damper 40 is pivoted at 41 and has an arm 42 secured thereto for operating the same. Secured to arm 42 is a spring 43 which is secured to a fixed support 44. The spring 43 serves to bias the arm 42 to the right, or in other words, to bias the damper 40 to the dotted line position wherein the damper is closed.

A damper motor 50 is provided for positioning the splitter damper 25 and the return air duct damper 40. This damper motor 50 is of the proportioning type shown in the patent to D. G. Taylor, No. 2,028,110, issued January 14, 1936. The motor of this patent is adapted to be controlled by a three-wire potentiometer. When the potentiometer is in its mid position, the motor is driven to a mid position through the action of a balancing resistance associated with the motor. Upon the control potentiometer moving to a short circuit position at either end, the motor is driven to the corresponding end of its movement and such movement is terminated by a limit switch. Where a potentiometer is used, the motor may assume any desired intermediate position. Inasmuch as only three positions are desired for the present application, a control potentiometer is not used. The motor is provided with three terminals 51, 52, and 53. When terminal 51 is connected to either terminal 52 or 53, the motor runs to the mid position under the control of the rebalancing potentiometer therein. When terminal 51 is connected to either terminal 52 or 53, the motor runs to one or the other of its extreme positions. The connection of terminal 51 to terminals 52 and 53 is controlled by a pair of relays 55 and 56 in a manner to be subsequently explained.

The motor 50 is provided with a shaft 57 on which is mounted a pair of cams 58 and 59. Cam 58 cooperates with a cam follower in the form of a lever 60. The cam is provided with two high points 61 and 62 and a low point 63. The motor 50 is designed to travel 180° and at one end of the motor travel the cam follower 60 is in engagement with the cam at 61 as shown, and at the other end with point 62. When cam follower 60 is in engagement with the cam at either point 61 or 62, it is in its full line position. In the intermediate position of the motor, the cam follower 60 engages the cam at point 63 and assumes the dotted line position shown on the drawings. The cam follower 60 is connected by means of a chain 65 or similar device to the arm 42 of the return air duct damper 40, the chain 65 extending over rollers 66. In the full line position of the cam follower, the return air duct damper 40 is in its open position. In the dotted line position of the cam follower, the return air duct damper 40 is in its closed position.

The cam 59, which as previously stated is also mounted on the motor shaft 57, is adapted to cooperate with a cam follower 70 and to position the cam in any one of three positions. When the motor is in one extreme position, the cam follower 70 engages the cam at point 71. When the motor is in its other extreme position, the cam follower 70 engages the cam 59 at point 72. When the motor is in its intermediate position,

the engagement of the cam follower 70 with the cam 59 is at point 73. When cam follower 70 engages the cam at point 71, it assumes the full line position thereof. When cam follower 70 engages the cam at point 72, the cam follower 70 assumes the upper dotted line position. When the engagement is at point 73, the follower 70 assumes the lower dotted line position. A chain 75 serves to connect the follower arm 70 with the arm 27 of the splitter damper 25, the chain passing over rollers 76. When the motor is in the extreme position shown, the splitter damper 25 occupies its normal intermediate position. When the damper motor is in the other extreme position so that the cam follower arm 70 is in its lowermost dotted line position, the splitter damper 25 assumes the left dotted line position. When the cam follower 70 is in the upper dotted line position, the splitter damper 25 assumes the right dotted line position.

The relay 55 comprises a relay coil 86 which cooperates with a pair of switch blades 87 and 88. The switch blades 87 and 88 are biased to the left, switch blade 88 being biased into engagement with a contact 89. Upon energization of relay coil 86, switch arms 87 and 88 are moved to the right into engagement with contacts 90 and 91, respectively.

The relay 56 comprises a relay coil 94 operatively associated with a switch blade 95. The switch blade 95 is adapted to cooperate with a contact 96. The switch blade 95 is normally biased out of engagement with contact 96 but is moved into engagement therewith by energization of coil 94. The switch blade 95 is shown in its energized position.

The operation of the damper motor and the gas valve 12 is controlled by a downstairs thermostat 100 and by an upstairs thermostat 101. The downstairs thermostat 100 is of a common type employing a clock to periodically change the setting thereof. Such a thermostat is shown in the patent to McNicoll No. 2,041,363 issued May 19, 1936. For an understanding of how such a clock thermostat is constructed reference is made to this patent. In the present drawings, such a thermostat is shown in schematic form. The thermostat proper comprises a bimetal element 102 secured to a contact arm 103. The contact arm is adapted to engage a fixed contact 104. The bimetal element is so arranged that the contact arm 103 moves to the left upon a drop in temperature. Associated with the contact arm 103 is a magnet 105 for imparting a differential to the thermostat. A bimetal element 102 is pivotally mounted at 106 and has secured thereto an adjusting arm 107 which adjusting arm is actuated by a clock 108. The clock 108 is adapted to also reciprocate a rod 109 connected to a pivotally mounted mercury switch support 110. The support 110 carries a mercury switch 111 which in the position shown is closed but which upon being tilted in a counter-clockwise direction is moved to open position. It is to be understood that the clock 108 is provided with means for setting the same so that at predetermined times at night and in the morning, the thermostat adjusting arm 107 and the switch 111 are moved. At night, the arm 107 is so moved as to rotate the bimetallic element 102 in a counter-clockwise direction to necessitate a greater drop in temperature to effect engagement of contact arm 102 with contact 104. At the same time, mercury switch 111 is rotated in a counter-clockwise direction to open its con-

tacts. In the morning, the reverse actions occur. The upstairs thermostat 101 is more or less conventional in form comprising a bimetallic element 115 to which is secured a contact arm 116 adapted to engage with a fixed contact 118 upon the temperature dropping to a predetermined point. A magnet 119 is associated with the arm 116 to impart a differential to the movement of the arm.

Operation of species of Figure 1

The various elements of the apparatus are shown in the position which they occupy during the normal day period. Under these circumstances, the relay 56 is maintained energized by the following circuit: from line wire 118 (one of two line wires leading to a commercial source of power not shown), through conductors 119 and 120, mercury switch 111, conductors 121 and 122, relay coil 94, and conductor 123 to the other line wire 124. The energization of relay 94 through the circuit just traced results in switch blade 95 being maintained in engagement with contact 96 as shown in the drawing. Under these circumstances, the center terminal 51 of the motor 50 is connected to terminal 53 by the following circuit: from terminal 51 through conductor 126, switch blade 95, contact 96, conductor 127, switch blade 88, contact 89, and conductor 128 to terminal 53. Under these circumstances, the motor is in one extreme position wherein the cams 58 and 59 and the cam followers 60 and 70 are in their full line positions. Under these conditions the dampers 25 and 40 are also in their full line positions. With the splitter damper 25 in its full line position, the air is divided between the two ducts 16 and 17 according to their respective duct capacities.

If the temperature of the downstairs room drops to the point at which the thermostat 100 is set so as to cause engagement of contact arm 103 with contact 104, the following circuit will be established to the gas valve 12: from line wire 118 through conductor 119, bimetallic element 102, contact arm 103, contact 104, conductors 130 and 131, valve 12, and conductor 132 to the other line wire 124. The establishment of this energizing circuit causes the valve 12 to open and admit gas to the gas burner, which gas burner is lighted by a pilot burner or other conventional means (not shown).

The ducts 16 and 17 are so proportioned that if the zone 22 is maintained at the proper temperature, the zone 19 is also maintained at the same temperature. The thermostat 101 in zone 19 can, accordingly, be set several degrees lower than the thermostat 100 with the assurance that the temperature in zone 19 will normally be substantially the same as that in living zone 22. If for some reason or other, however, the temperature in the upstairs zone 19 should fall down to the setting of the upstairs thermostat 101 to cause engagement of contact arm 116 with contact 118, the following circuit is established to relay 55: from line wire 118 through conductors 119 and 120, switch 111, conductor 121, conductor 133, bimetallic element 115, contact arm 116, contact 118, conductor 134, relay coil 86, and conductor 135 to the other line wire 124. The energization of relay coil 86 by reason of the establishment of the last named circuit, causes switch arm 88 to separate from contact 89 and to move into engagement with contact 91. The energization of the relay also causes switch blade 87 to be moved into engagement with contact 90. The moving of switch blade 87 into engagement

5 with contact 90 establishes the following circuit to the gas valve 12: from line wire 118 through conductor 137, switch blade 87, contact 90, conductors 138 and 131, valve 12, and conductor 132 to the other line wire 124. This results in the energization of valve 12 so as to cause the operation of the same if the same has not previously been opened as the result of thermostat 100 calling for heat.

10 The moving of switch blade 88 from engagement with contact 89 and into engagement with contact 91 results in the interruption of the circuit between motor terminals 51 and 53 and in the establishment of the following circuit between motor terminals 51 and 52: from terminal 51 through conductor 126, switch blade 95, contact 96, conductor 127, switch blade 88, terminal 91, and conductor 140 to the terminal 51. The connection of terminals 51 and 52 causes the motor 20 to run to its other extreme position displaced 180° from the position indicated in full lines. The cam follower 60 now engages at point 62 of the cam 58, its position being unchanged. Consequently, this movement of motor 50 does not affect the position of the return air damper 40. The cam follower 70 in the new position of the motor engages point 72 of the cam 59, which as previously indicated, results in the cam follower 70 assuming the upper dotted line position. Under these conditions, the splitter damper 25 is moved to 25 its right dotted line position. It will be noted that in this position of the splitter damper 25, the air to duct 17 is partially cut off and the proportional amount of air admitted to duct 16 is increased. This position of the splitter damper 30 may be referred to as the "pick-up" position and is the position that the damper assumes during the pick-up period. With the damper in this position a relatively large proportion of the heated air is delivered to duct 16 with the result 35 that zone 19 receives a larger than normal proportion of the air. This increase in the proportion of the air will result in the temperature of zone 19 quickly rising, which quick rise is desirable in view of the fact that since thermostat 101 is calling for heat, the temperature in zone 19 is at least several degrees below that of zone 22. As soon as thermostat 101 becomes satisfied, the various elements are restored again to the 40 position shown in the drawings.

50 The operation which has been described thus far is that which takes place during the normal day period. When the time arrives that the switch 111 is opened and the setting of thermostat 100 is lowered, as previously explained. The opening of switch 111 results in the deenergization of relay 56. The opening of switch 111 also 55 interrupts the only circuit to thermostat 101 and consequently takes the control of the heating plant and damper motor 50 away from this thermostat. The deenergization of relay 56 results in switch blade 95 separating from contact 96. This, in turn, results in motor terminal 51 being disconnected from both motor terminals 52 and 53. The motor is now controlled solely by its internal rebalancing potentiometer which serves to run the motor to its mid position. In the mid position of the motor, the cam followers 60 and 70 engage points 63 and 73 of their respective means. The engagement of cam follower 60 with point 63 of cam 58 results in its assuming the upper dotted line position. In this position of cam follower 60, the return air damper 75 40 is in its closed position as indicated in dotted

lines. The closure of the damper 40 prevents any air from being returned from the upstairs zone to the heating plant and consequently prevents the cold air in the bedrooms from being delivered to the furnace.

The movement of cam follower 70 into engagement with the point 73 of cam 59 results in the cam follower 70 being moved to its lowermost dotted line position so that the splitter damper 25 is moved to its left dotted line position. It will be noted that in this position of the splitter damper, the proportional amount of air delivered to the zone 19 is materially decreased. In this manner, it is assured that very little heated air will be delivered to the zones in which windows may be open. At the same time, some air is delivered so that the room temperature will not drop to an excessively low value.

During the shut-down period, the thermostat 100 still retains control of the gas valve 12. Thus, whenever the temperature gets to the lower setting of thermostat 100, the gas valve is opened to supply gas to the furnace. The result of this is that the zone 22 is maintained at the desired night temperature with a minimum expenditure of fuel. The majority of the heated air during the entire shut-down period is delivered to the zone 22 which has only the normal heat loss. A small amount of air is delivered to zone 19 which zone is the one with the abnormally high temporary heat loss. While a portion of the heated air is delivered to this zone, the cold air therefrom cannot enter the furnace.

When the time comes for the initiation of the pick-up period, the temperature in zone 19 will obviously be very far below the setting of the thermostat 101. Consequently, when switch 111 is reclosed in the morning by the clock 103, the contact arm 116 of thermostat 101 will be in engagement with contact 118. This will result in the energization of both relays 55 and 56. The energization of relay 56 will be effected solely by the closure of switch 111 by the circuit previously traced. The energization of relay 55 will be effected by the joint closure of thermostat 101 and switch 111 to effect the closure of the circuit traced previously. The result of the energizations of both relays 55 and 56 is that terminal 51 will now be connected to terminal 52 in the same manner as previously traced in connection with the thermostat 101 calling for heat during the day period. This will result in the motor 50 going to the extreme position in which cam follower 60 is in engagement with point 62 of cam 58 and follower 70 in engagement with point 72 of cam 59. Under these conditions, the damper 40 will be in the full line position wherein return air from zone 19 can again return to the furnace. The splitter damper 25 will be moved to the right dotted line position so that the greater proportion of the air is delivered to the upstairs zone 19. The cam 59 can be so designed that the increase in proportion of air delivered to the upstairs zone is adequate to cause the two zones 19 and 22 to approach the desired day temperature at approximately the same time. Before the temperature in the upstairs zone reaches the temperature which it is desired to maintain, or a temperature at which thermostat 100 is set during the day, the thermostat 101 will open interrupting the circuit to relay 55. The interruption of the circuit to relay 55 restores the various elements to the positions shown in the drawing in full lines wherein the air is delivered to zones 19

and 22 in the proportions determined by ducts 16 and 17.

It will be noted that in the improved system of the present invention, recognition is made of the fact that the associated dwelling is normally subjected to an abnormally high heat loss during the night period. Provision is made for preventing the undue waste of heat during this night shutdown period and also for providing a quick but balanced pick-up in the temperature of the two zones in the morning. This, moreover, is accomplished with relatively simple apparatus.

Species of Figure 2

In some cases it may be desired to have the upstairs thermostat normally controlling during the daytime and to have the same set at the value at which it is desired to maintain rather than at some value several degrees below that which is desired. Under these conditions, it is not desirable to have the splitter damper move to the pick-up position each time that the upstairs thermostat calls for heat. I have, accordingly, provided a species in which the pick-up period is controlled by a timing mechanism so that a pick-up period of predetermined length is provided. In order to enable a clearer comparison of the two figures, the various corresponding elements of the two systems have been designated by identical reference characters and will not be again described. Since the cams and the dampers operated thereby are identical with those of the preferred species, these are not shown in Figure 2.

In lieu of the relay 55 a relay 155 is employed in this species. This relay comprises a relay coil 186 which is associated with a single relay blade 188. The relay blade 188 is biased into engagement with contact 189 and is adapted to be moved into engagement with a contact 191.

In lieu of the clock thermostat 100 of the preferred species, a clock thermostat 200 is provided in this species. The thermostat portion of the clock thermostat 200 is identical to that of clock thermostat 100, the only change being in the switching function performed by the clock. The thermostat proper comprises a bimetal element 202 to which is secured a contact arm 203 adapted to engage with a contact 204. A magnet 205 is provided for a purpose similar to that of the magnet 105 of the preferred species. The clock in this thermostat is designated by the reference numeral 208 and is adapted to actuate an adjusting arm 207 for bimetal 202 and to reciprocate a rod 209 which is connected to a pivotal support 210 for a mercury switch 211. In addition to the switch 211 corresponding to switch 111 of the previous species, a second switch 214 is provided in this species. This second switch 214 is also of the mercury type, being shown in the open position in the drawings. The clock is designed to close this switch at the beginning of the pick-up period and to open the same at the end thereof. Thus in a typical case, the switch 214 might be closed by the clock at five o'clock in the morning and opened at six o'clock.

Operation of species of Figure 2

The various elements of this species are shown in the position they occupy during the normal day period. It is to be understood that the dampers and other associated apparatus are in the same position as they are shown in Figure 1. Under these conditions, the relay coil 56 is maintained energized by a circuit corresponding

identically to the energizing circuit therefor in the species of Figure 1, this energizing circuit being as follows: from line wire 118 through conductors 219, 296, and 220, switch 211, conductors 221 and 222, relay coil 56, and conductor 223 to the other line wire 124. Under these conditions, the damper motor terminals 51 and 53 are connected as follows: from terminal 51 through conductor 226, switch blade 95, contact 96, conductor 227, switch blade 188, contact 189, and conductor 228 to the other terminal 53. Thus terminals 51 and 53 are connected together just as they are in the full line positions of the element in Figure 1.

If the downstairs thermostat 200 calls for heat, an energizing circuit is established to the valve 12 as follows: from line wire 118 through conductors 219 and 296, bimetallic element 202, contact arm 203, contact 204, conductors 297 and 298, gas valve 12, and conductor 299 to the other line wire 124. When such a circuit is established, the gas valve is open and the gas is admitted to the furnace in the manner previously described.

When the upstairs thermostat 101 calls for heat, a circuit is established to the gas valve as follows: from line wire 118 through conductors 219, 296, and 220, switch 211, conductors 221 and 300, bimetal element 115, contact arm 116, contact 118, conductors 301 and 298, gas valve 12 and conductor 299 to the other line wire 124. It will be noted that, with this species, upon the thermostat 101 calling for heat, only the gas valve is energized. There is no change in the position of the damper motor 50 as in the preceding case. This feature is advantageous where it is desired to have thermostat 101 set at the temperature which it is desired to maintain in the zone 19.

When the time comes for the shut-down period, the clock 208 is effective to open switch 211. This deenergizes relay 56 just as in the preferred species to cause the damper motor to run to the mid position which is the shut-down position. The opening of switch 211 also interrupts the circuit to thermostat 115 so that this thermostat can no longer open the valve 12. It will be noted that the action upon shut-down is exactly the same as in the species of Figure 1. In other words, control is taken away from the upstairs thermostat and the amount of air delivered to the upstairs zone is decreased.

Upon the time arriving for the morning pick-up period the clock 208 in this species is effective to not only reclose switch 211 but also to close switch 214. The closure of switch 211 reenergizes relay coil 56 and restores control of the thermostat 116 over the gas valve 12. The clock also functions to again raise the setting of the thermostat 200 so that this thermostat will call for heat. As in the previously described species, it is necessary that relay 155 be energized for the pick-up period. In the previously described species, this energization of relay 155 was accomplished through the closure of thermostatic switch 101. In the present species, this energization of relay 155 is accomplished by the closure of switch 214. Upon closure of this switch, the following circuit is established to relay 155: from line wire 118 through conductors 219 and 305, switch 214, conductor 306, relay coil 186, and conductor 307 to the other line wire 124. The energization of relay coil 186, as a result of the establishment of this circuit, causes switch blade 188 to move into engagement with contact 191, establishing the following circuit: from motor ter-

51 through conductor 226, switch blade 95, contact 96, conductor 227, switch blade 188, contact 191, and conductor 308 to the other terminal 52. A shorting of terminals 51 and 52 has the same effect as in the previous species, namely, to drive the motor 50 to the pick-up position.

The motor continues to remain in the pick-up position until a predetermined period of time has elapsed, at the end of which, switch 214 is moved to the position shown in the drawings wherein it is in open circuit position. Relay 155 will then be deenergized so that switch blade 188 again engages contact 189 to cause the motor to assume the normal day position. The clock can be adjusted to provide a pick-up period corresponding to the weather conditions. For example, during very cold weather a longer pick-up period is necessary than in mild weather.

It will be seen that with the last named species, the splitter damper is moved to its pick-up position only during the normal pick-up period. Moreover, with the last described species, the thermostat in the sleeping zone may be set at the temperature which it is desired to maintain in the zone.

While I have described my invention in connection with a heating system, it is to be understood that the same is applicable to any air conditioning system wherein it is desired to maintain this value of a condition in one of the zones during a certain predetermined period. While I have disclosed a damper in the return air duct leading from the zone occupied at night, it is to be understood that if desired the return duct from this zone may be entirely omitted, in which case there obviously would be no need for such a damper. In general, while I have shown and described the invention in considerable detail, it is to be understood that this is only for purposes of illustration and that the scope of the invention is limited only by the scope of the appended claims.

I claim as my invention:

1. In an air conditioning system for an enclosure having a plurality of zones, air conditioning means, means for conveying the conditioned air to said plurality of zones, means for reducing the delivery of air to one of said zones for a predetermined period of time, and means operative after the termination of said period of time to reduce the portion of the air supplied to the rest of the enclosure and to supply a greater than normal portion of the total air to said one zone until the condition in said zone attains a predetermined value.

2. In an air conditioning system, air conditioning means, means for conveying the conditioned air to a plurality of zones, means for proportioning the air delivered to said zones, condition responsive means in one of said zones normally controlling said air conditioning means, means for causing said proportioning means to reduce the amount of air delivered to one of said zones for a predetermined period of time and to interrupt the control of said air conditioning means by said condition responsive means during said period, and means including said condition responsive means operative upon the termination of said period to cause said proportioning means to deliver to said one zone a greater than normal portion of said air until the condition in said zone has attained the value for which said condition responsive means is set to maintain.

3. In an air conditioning system, for an en-

closure having a plurality of zones air conditioning means, means normally effective to distribute the conditioned air among said zones in predetermined proportions, condition responsive means in one of said zones normally controlling said air conditioning means, means for causing said proportioning means to reduce the amount of air delivered to said one zone for a predetermined period of time and to interrupt the control of said air conditioning means by said condition responsive means during said period, and means operative upon the termination of said period to cause said distributing means to deliver to said one zone a greater than normal portion of said air for a second predetermined period of time.

4. In a warm air heating system for a residence having a first zone consisting of rooms primarily occupied for sleeping purposes and a second zone consisting of rooms primarily occupied during the day, means for heating the air, means for normally distributing the heated air between said zones in predetermined proportions, means for reducing the delivery of air to the first zone during the period the same is used for sleeping purposes, and means operative after the termination of said period to supply a greater than normal portion of air to said first zone while reducing the flow of air to said second zone.

5. In an air conditioning system for an enclosure having a plurality of zones; air conditioning means; means for conveying the conditioned air to said plurality of zones; means for proportioning the air delivered to said zones; condition responsive means in all of said zones, each normally controlling said air conditioning means; and means to interrupt the control of said air conditioning means by the condition responsive means in all but one of said zones during a predetermined period, to change the setting of the condition responsive means in said one zone so as to cause the same to maintain during said period a new value of the condition requiring less operation of the conditioning means, and to cause said proportioning means to increase the proportionate amount of the air delivered to said one zone during said period.

6. In an air conditioning system for an enclosure having a plurality of zones; air conditioning means; means for conveying the conditioned air to said plurality of zones; means for proportioning the air delivered to said zones; condition responsive means in all of said zones, each normally controlling said air conditioning means; and means to interrupt the control of said air conditioning means by the condition responsive means in all but one of said zones during a predetermined period, to change the setting of the condition responsive means in said one zone so as to cause the same to maintain during said period a new value of the condition requiring less operation of the conditioning means, and to cause said proportioning means to increase the proportionate amount of the air delivered to said one zone during said period; said means being operative at the expiration of said period to restore the control of said air conditioning means to all of said condition responsive means, to restore the setting of said condition responsive means in said one zone, and to cause said proportioning means to temporarily decrease the proportionate amount of air delivered to said one zone.

7. In an air conditioning system for an enclo-

sure comprising two zones, air conditioning means, means for conveying the conditioned air to said zones, said means normally being operative to divide the conditioned air between the zones in such a manner that the same value of the condition is maintained in both of the zones, condition responsive means in each of the zones controlling the operation of the air conditioning means, the condition responsive means in one of said zones being set to maintain the desired value of the condition and the condition responsive means in the other zone being set to maintain a value of the condition requiring less operation of the condition changing means, and means operative when said last named condition responsive means calls for conditioning to supply a greater than normal portion of the conditioned air to said other zone.

8. In an air conditioning system for an enclosure comprising two zones, air conditioning means, means for conveying the conditioned air to said zones, said means normally being operative to divide the conditioned air between the zones in such a manner that the same value of the condition is maintained in both of the zones, condition responsive means in each of the zones controlling the operation of the air conditioning means, the condition responsive means in one of said zones being set to maintain the desired value of the condition and the condition responsive means in the other zone being set to maintain a value of the condition requiring less operation of the condition changing means, means operative when said last named condition responsive means calls for conditioning to supply a greater than normal portion of the conditioned air to said other zone, and further means operative during a predetermined period to render ineffective said last named condition responsive means and to cause said air conveying means to convey a less than normal portion of the conditioned air to said other zone.

9. In a heating system for an enclosure having a plurality of zones one of which has an abnormally high heat loss during certain periods, fluid heating means, thermostatic means in a different one of said zones for normally controlling said fluid heating means, means for normally distributing the heated fluid among said zones in predetermined proportions, means for decreasing the flow of fluid to the rest of the enclosure for a predetermined time following such a period of abnormally high heat loss in said one zone whereby a greater than normal portion of the total fluid is conveyed to said one zone, and means for causing continuous operation of said fluid heating means independently of said thermostatic means during the time in which the flow of heated fluid to the other zones is reduced.

10. In a heating system for an enclosure having a plurality of zones one of which has an abnormally high heat loss during certain periods, fluid heating means, a thermostatic means in a different one of said zones for normally controlling said fluid heating means, means for normally distributing conveying the heated fluid among said plurality of zones in predetermined proportions, and means operative for a predetermined period of time following such a period of abnormally high heat loss in said zone to decrease the flow of fluid to the rest of the enclosure and thereby increase the portion of the fluid going to said one zone.

11. In a warm air heating system for a residence having a first zone consisting of rooms

primarily occupied for sleeping purposes and a second zone consisting of rooms primarily occupied during the day, means for heating the air, means for normally distributing the heated air between said zones in predetermined proportions, and means for temporarily decreasing the proportion of fluid distributed to said second zone at the expiration of a period during which said first zone was used for sleeping, thereby increasing the proportion of fluid distributed to said first zone.

12. In a system of the character described, means defining a plurality of enclosed spaces, means for heating air, means for delivering the heated air to the respective enclosed spaces, a temperature responsive device located in one of said spaces, means responsive to the operation of said device for controlling the operation of said heating means, a time switch located in a second space, and means responsive to the operation of said time switch for impeding the flow of heated air to the spaces other than that in which said time switch is located.

13. In a system of the character described, means defining a plurality of enclosed spaces, means for heating air, means for delivering the heated air to the respective enclosed spaces, a temperature responsive device located in one of said spaces, means responsive to the operation of said device for controlling the operation of said heating means, a time switch located in a second space, and means responsive to the operation of said time switch for impeding the flow of heated air to the spaces other than that in which said time switch is located and for impeding the return of medium from which heat has been extracted from the spaces other than that in which said time switch is located.

14. In a system of the character described, means defining a plurality of enclosed spaces, means for conditioning air, means for delivering the conditioned air to the respective enclosed spaces, condition responsive means located in one of said spaces, means operable by said condition responsive means for controlling the operation of said air conditioning means, time-controlled means, and means operable by said time-controlled means to reduce the amount of air delivered to said one space for a predetermined period of time and to interrupt control of said air conditioning means by said condition responsive

means during said period, said last-named means being operative at the expiration of said predetermined period to increase temporarily the amount of air delivered to said one space.

15. In an air conditioning system for a building having a plurality of zones, air conditioning means, means for normally distributing the supply of conditioned air among said zones in proportions determined in accordance with the relative demands of said zones so as to maintain a condition of the air in each zone at a predetermined value, means for decreasing for a predetermined time the proportion of air delivered to one of said zones without regard to the demand therein, and means operative at the expiration of said predetermined time for increasing temporarily the proportion of air delivered to said one zone so as to accelerate restoration of said condition in said one zone to said predetermined value.

16. In a heating system for a building having a plurality of zones, fluid heating means, means for distributing the supply of heated fluid among said zones in proportion to their respective normal heat losses so as to maintain each of said zones at a predetermined temperature, one of said zones being subject to periods of abnormally high heat loss during which the temperature in said one zone falls below said predetermined temperature, and means operable at the expiration of one of said periods of abnormally high heat loss to increase temporarily the proportion of fluid distributed to said one zone so as to accelerate the return of said one zone to said predetermined temperature.

17. In a heating system for a building having a plurality of zones, fluid heating means, means for distributing the supply of heated fluid among said zones in proportion to their respective normal heat losses so as to maintain each of said zones at a predetermined temperature, one of said zones being subject to periods of abnormally high heat loss during which the temperature in said one zone falls below said predetermined temperature, and means operable at the expiration of one of said periods of abnormally high heat loss to increase the proportion of fluid distributed to said one zone until said one zone regains its predetermined temperature.

SAMUEL S. LAWLER.

CERTIFICATE OF CORRECTION.

Patent No. 2,290,757.

July 21, 1942.

SAMUEL S. LAWLER.

It is hereby certified that error appears in the printed specification of the above numbered patent requiring correction as follows: Page 6, second column, line 66, claim 10, strike out "conveying"; and that the said Letters Patent should be read with this correction therein that the same may conform to the record of the case in the Patent Office.

Signed and sealed this 12th day of January, A. D. 1943.

Henry Van Arsdale,
Acting Commissioner of Patents.
